HAND STAMP

Frank R. Anderson, Montebello, and Albert J. Castro, Cudahy, Calif., assignors to Westates Space-Era Products Inc., Los Angeles, Calif., a corporation of California

Filed Oct. 30, 1967, Ser. No. 9,202

Term of patent 14 years

U.S. Cl. D64—10
Int. Cl. D18—99

FIG. 1.

FIG. 2.

FIG. 3.

FIG. 4.

FIG. 5.

FIG. 1 is a front elevational view of a hand stamp showing our new design;

FIG. 2 is a top plan view thereof;

FIG. 3 is a bottom plan view, the broken lines being merely an indication of a conventional rubber stamp;

FIG. 4 is a side elevation thereof, the side opposite thereto presents a mirror image; and

FIG. 5 is another embodiment of the hand stamp shown in FIG. 1 wherein the bottom body portion has been widened and the annular bands on the handle portion are in different arrangement.

The backs of the hand stamps shown in FIGS. 1 and 5 are similar to the front except that the front notched portion has been omitted from the backs.

We claim:

The ornamental design for a hand stamp, substantially as shown and described.
